UNITED STATES PATENT OFFICE.

VLADIMIR VON RACZYNSKI, OF POSEN, GERMANY.

HAULING DEVICE FOR AGRICULTURAL MACHINES.

1,104,312.

Specification of Letters Patent.

Patented July 21, 1914.

Application filed March 9, 1914. Serial No. 823,499.

To all whom it may concern:

Be it known that I, VLADIMIR VON RACZYNSKI, a subject of the Emperor of Germany, and residing at 20 Wilhelmstrasse, 5 Posen, Germany, have invented certain new and useful Improvements in Hauling Devices for Agricultural Machines, of which the following is a specification.

The invention has reference to improvements in power driven portable hauling devices driven by internal combustion engines for operating agricultural machinery such as plows.

As is well known, combustion engines, or 15 Diesel engines, or the like, are, as normally constructed, not well adapted for taking overloads. It is therefore, contrary to the case with steam engines, necessary to put the load on to such engines always very 20 gradually by means of friction clutches. In this manner, however, the amount of time wasted is increased to an impermissible degree, and, when the clutch is switched in carelessly, very considerable difficulties and 25 delays in the working may be caused, which it is absolutely essential to avoid in power-driven plowing, quite apart from the fact that the wear and tear of the clutches, which, in view of the high power required for the 30 rapid shifting onward of the portable hauling device are very heavy and expensive, is very great owing to the frequent employment of said clutches.

It has already been proposed, to provide a 35 steam portable hauling device for operating plows with an extra gear for propelling it along at a slower rate when it has to be moved on bad ground, besides the usual traveling gear, and to put this extra gear 40 for the slow speed into action, for the purpose of saving time, while the winding-drum is still revolving during the latter part of the travel of the plow toward the hauling device, so as to move the hauling 45 device onward to the extent of the width of one furrow.

In view of that which has been set forth above with regard to hauling devices with 50 explosion engines, it will be clear that also the last mentioned arrangement is not suitable for this class of hauling devices, namely, those with explosion engines. By the present invention, however, the practical employment of portable hauling devices for 55 operating plows with explosion engines is rendered possible by the fact that, instead

of the device being provided with the above-mentioned slow-speed traveling gear, it is provided with a gear which is of such high ratio, *i. e.* it gives such a slow speed of 60 travel, that it cannot come into question at all for traveling purposes on roads, but is on the other hand capable of propelling the hauling device laterally during the whole 65 plowing operation at an almost imperceptible speed. If one takes, for example, a field 250 yards in length, the engine will move laterally to the extent of one furrow's width, or say 2 yards, which corresponds to a rate of progression of about $\frac{1}{3}$ ins. per sec. 70 which is almost imperceptible to the eye. By this extraordinarily slow rate of progression, the work of moving the hauling device is distributed uniformly over the whole of the time that the plowing operation is going on, so that the explosion motor is correspondingly uniformly loaded and the above mentioned drawbacks are avoided. 75

A preferred form of the invention will now be described with reference to the accompanying drawings in which:

Figure 1 is a side elevation of the rear portion of the hauling device in accordance with the invention. Fig. 2 is a plan of the parts shown in Fig. 1, and Fig. 3 is a rear 85 sectional elevation of part of the device shown in Fig. 1, drawn to a larger scale.

Referring to the drawings the engine shaft *p* driven by the engine (not shown) is provided with three slidable gears *g* each 90 of which is capable of enmeshment with one of the three gears *r* upon the intermediate shaft *s* carrying the bevel pinion *m*. The cable drums *d* and *e* are driven off this intermediate shaft *s* by means of the bevel pinions *t*, shaft *c* and pinion *v* which is slidable 95 in a vertical direction so that it can mesh with the peripheral teeth of either of the aforesaid drums. It will be seen from Fig. 3 that the pinion *v* does not drive the drums 100 *d* and *e* simultaneously but is slidable along the shaft *c* to mesh with the drums *d* and *e* alternately. One of the bevel gears *t* is slidable along its shaft and is moved out of 105 enmeshment with the other bevel pinion *t* while the machine is traveling on the road. The tractor wheels *n* and *o* are driven off the intermediate shaft through bevel pinions *m*, *l*, and *k*; the pinion *m* is fixed on the end of the shaft *s* whereas the pinions *k* and *l* 110 are slidable on the shaft *i* and only one of these pinions is in mesh with the pinion *m*.

if the machine is traveling on the road. For traveling in a forward direction the pinion *l* meshes with the pinion *m* and for traveling in a backward direction the pinion *k* 5 meshes with the pinion *m*. The drawing shows the machine in the field and therefore neither of the pinions *k* or *l* is in mesh with the pinion *m* but the pinions *t* are in mesh with each other. The pinions *k* and *l* are 10 mounted on a shaft *i* at the other end of which is mounted a pinion *v'* gearing with a spur wheel *w* on the shaft *x* which has mounted thereon a small pinion *y* gearing with the spur wheel *z* rigidly mounted on 15 axle of the wheels *n* and *o*. A lantern wheel *b* is mounted on the shaft *i* and normally engaged by a pawl *h* mounted on a swinging lever *g* to the lower end of which is attached the arm *f* adapted to be actuated by the trip 20 or cam *a* on the shaft *c*. The pinion *m* is not in mesh with the wheel *k* or *l* but the pinions *t* are in mesh and therefore the shaft *c* is rotated driving alternately the drums *d* and *e*. During each revolution of the shaft 25 *c* the lever *g* is swung back and forth and the pawl *h* thereby rotates the wheel *b* to the extent of one tooth. If for instance the wheel *b* has 30 teeth the shaft *i* makes one revolution while the shaft *c* makes 30 revolutions so that a very slow and steady 30 progression is effected.

Having now described my invention what I claim as new and desire to secure by Letters Patent is:—

35 1. A power driven portable hauling device for operating agricultural machines

such as plows comprising in combination with the traction wheels of means including an internal combustion engine for driving said wheels at a uniform speed such that the 40 hauling device will move slowly through a predetermined distance.

2. A power driven portable hauling device for operating agricultural machines moving over a plurality of courses in a field, 45 comprising in combination with the traction wheels, of means including an internal combustion engine for driving said wheels at a uniform speed over a distance equal to one 50 of the courses in the field during the time that the agricultural machine or machines completes a course in said field.

3. A power driven portable hauling device for operating plows comprising in combination with the traction wheels, of means including an internal combustion engine for driving said wheels at a uniform speed to the extent of one furrow during the period 55 of time taken by the plow to plow a furrow.

4. A power driven portable hauling device for operating plows comprising a continuously operating internal combustion engine and reduction gearing for causing said engine to drive the hauling device at an extremely low operating speed.

In testimony whereof I have signed my name to this specification in the presence of two subscribing witnesses.

WLADIMIR VON RACZYNISKI.

Correction in Letters Patent No. 1,104,312.

It is hereby certified that in Letters Patent No. 1,104,312, granted July 21, 1914, upon the application of Wladimir von Raczynski, of Posen, Germany, for an improvement in "Hauling Devices for Agricultural Machines," an error appears in the printed specification requiring correction as follows: Page 1, line 90, for the reference-letter "g" read *g*; and that the said Letters Patent should be read with this correction therein that the same may conform to the record of the case in the Patent Office.

Signed and sealed this 22nd day of December, A. D., 1914.

[SEAL.]

J. T. NEWTON,

Acting Commissioner of Patents.
